DUST COLLECTOR

Joseph Butera, San Jose, Calif., assignor of one-half to Victor J. Lo Bue and Samuel Di Maria, both of San Jose, Calif., jointly

Application June 19, 1939, Serial No. 279,926

9 Claims. (Cl. 51—273)

The present invention relates particularly to means for collecting the dust formed in the operation of shoe repairing machinery.

In repairing shoes it is now common practice to perform many of the required operations in finishing, such as wire-brushing, sanding, polishing, etc., by means of a machine known as a finishing machine.

Since a great deal of extremely fine dust is produced in some operations, particularly in the sanding operations, many attempts have been made to equip these machines with devices that would automatically remove the dust promptly upon production, and at the point of its formation.

Heretofore such devices as above referred to have been inefficient, largely because so constructed and arranged that the flow of air therethrough is unduly impeded. Such devices include a blower arranged to suck the air from the area immediately surrounding a sander or other tool, and force it into a canvas bag. While the air does pass outwardly through the walls of the bag and leave the dust confined therein, its movement is so obstructed that a pressure is built up within the bag, and the blower must operate against this pressure within the bag. The result is that the greater the pressure built up in the dust bag the less effective is the suction operation, the dust accumulating around the mouth of the suction tube and flying off into the atmosphere where it can be breathed by the operator or where it can settle upon other portions of the machine or surrounding objects.

It is, therefore, one object of the present invention to provide a dust collector for shoe repairing machinery that is so constructed and arranged that it will instantly remove all of the dust formed by a given tool at the point of its formation, and deposit it in a given receptacle, discharging the air back to the atmosphere dust free.

It is another object of the invention to provide means of the character indicated that may be readily adapted for use in connection with any finishing machine of any make, and one that will be economical to manufacture, simple in form and construction, positive in operation, and highly efficient in its practical application.

In the drawings:

Figure 1 is a front elevation of a portion of a shoe repairing finishing machine embodying my invention.

Figure 2 is a view on line 2—2 of Figure 1.

Figure 3 is an enlarged section through the

discharge portion of the blower and the pipe connection thereto.

Figure 4 is an enlarged section through the settling drum, on line 4—4 on Figure 2.

Figure 5 is a greatly enlarged section through the dust settling box, on line 5—5 of Figure 6.

Figure 6 is a front elevation of a portion of the settling box.

Figure 7 is a sectional view on line 7—7 of Figure 4. Figure 8 is a section on 8—8 of Figure 5.

In the particular embodiment of the invention herein shown and described, I indicate the general frame of a finishing machine at 1, the drive shaft being indicated at 2 and the tool shaft at 3 with the connecting driving belt at 4, and the several grinding, polishing or sanding tools on shaft 3 as at 5. The dust removing tube is shown at 6, with the several hoods 7 communicating therewith and extending upwardly and over the tools 5. Drawing the air from tube 6 is a blower fan 8 with its discharge at 9 and operated by means of a motor through the medium of belt drive 10.

The foregoing described arrangement, with the exception of the provision of the motor 11, illustrates in a more-or-less formal manner, what is already well established practice, and therefore is not developed in detail.

In effecting my invention I mount a tubular member 12 on the discharge outlet of the blower 8, incorporating a curved wall 13 to direct the dust-laden air directly to the pipe 14.

The pipe 14 leads upwardly to the under side of a cylindrical drum 15 with which it communicates at 16, near one end thereof.

The drum 15 has a long narrow slot 17 formed in the bottom thereof and extending longitudinally thereof, communicating with a hopper 18. The hopper 18 is formed by side walls 19 underlying the full length of the slot 17 and mounted on the drum 15 to depend therefrom as shown, the said walls converging to discharge into a short vertically disposed tube 20.

At 21 is a housing seated on frame 1 and divided into two chambers as 22 and 23 communicating by means of a narrow slot 24.

The housing 21 is disposed to extend from the front to the rear of the frame 1, its rear wall forming one side of the slot 24, and the front wall of chamber 22 being substantially in vertical alignment with the front edge of tube 20, the tube 20 therefore discharging into the forward portion of the chamber 22 at its top, and

the slot 24 discharging from the chamber 22 from the bottom rear portion thereof.

Mounted in the chamber 22 is a curved baffle plate or chute extending from the forward upper end of the chamber to the slot 24 as at 25.

At 26 is a shaft extending laterally through the chamber 22 above the slot 24 and fitted with three vanes as 26a of a length to sweep over the lower end of plate 25. The shaft is rotated in the direction indicated by arrow 27 by means of a belt drive connection 28 to the main drive shaft 2.

That portion of chamber 22 in the rear of plate 25 as at 28 has an air leak 29 to the atmosphere, the discharge of air at this point being controlled by means of a thumb-screw 30.

The front of the chamber 23 is closed with a double closure, the inner one of which comprises a door member 31 grooved at 32 to seat on a tongue 33 and fitting snugly upon all sides except the top where it is spaced from the top of the chamber as at 33a. On the inner side of the door 31 is mounted a strip of sheet metal 34 curved upwardly and inwardly as at 35, with its free edge spaced slightly from the top of the chamber.

The outer door 36 is hinged along the bottom edge as at 37 and spaced from the top as at 38, and is normally held in a closed position by pins 38a seating in the top edge thereof, the pins being mounted on a transverse angle-iron 39 which seats on the top of the chamber with one flange extending downwardly over the passage 33 over the door 36 and in spaced relation to the door as at 40. The part 39 is mounted on the upper ends of vertical bars 41 which are vertically adjustable in bearings 42.

To clean the chamber the member 39 is raised to release door 36 which will then swing open on hinges 37, and the door part 31 may then be lifted out of place.

When the device is in operation the dust laden air is discharged into drum 15 where the velocity of its flow is very substantially reduced, thereby permitting the dust to settle to the bottom thereof where it is carried through slot 17 to tube 20 and thence to plate 25. Since these parts have a greater cross-sectional area than the pipe 14 the velocity of the air is still comparatively slow, and its turbulence eliminated.

In the chamber 22 most of the dust is deposited on plate 25 down which it slides, being pushed into the chamber 23 by the rotating vanes 26a. The air is expanded in chamber 22 and consequently its rate of flow is so reduced that it flows gently through slot 24. Its force is still further reduced at this point by permitting some air to pass out through leak 29, this air carrying no perceptible dust because of its location, and because the small amount of air flowing does not create suction.

When the air passes into chamber 23 the dust accumulates at the lowest point 43 because there is no turbulence tending to keep it suspended in the air, the air draining out of the chamber by flowing along its ceiling and discharging through the slots or openings above the doors.

It will be noted that the flow of air through the passage 24 is controlled by the three vanes 26a in such a manner that when they are in the position shown in Figure 5 the flow of air is momentarily arrested and the whole body loses the velocity imparted by the blower and maintained in part up to this point. As the vanes 75 rotate they push the material accumulated on

plate 25 through the passage and at the same time permit the air to flow therethrough.

Although a certain specific embodiment of the invention has been herein illustrated and described, it will be understood that various alterations in the details of construction and mode of assembly may be made without departing from the scope of the invention as indicated in the appended claims.

I claim:

1. In a dust collecting system, the combination of a housing formed to define a pair of chambers, one superimposed upon the other, a passage connecting the chambers at one end thereof, a dust passage leading into the upper portion of the first chamber, an inclined plate leading from the upper passage to the first mentioned passage, rotatable means disposed over the first passage in parallel relation therewith, and brushing means mounted on the rotatable means disposed to push material from the plate through the said first passage.

2. In a dust collecting system, the combination of a housing forming a dust collecting chamber, a second chamber disposed over the first chamber, a passage connecting the two chambers, a passage leading to the top of the second chamber, a baffle plate disposed in the second chamber to guide material entering the top passage to the first passage, and devices rotatively mounted over the first passage and disposed to engage material on the plate and push it into the said first passage.

3. In a dust collecting system, the combination of a chamber having a passage leading into the top portion thereof at one side thereof, a discharge passage leading from the bottom thereof at the opposite side thereof, a baffle plate leading from the first passage to discharge into the second passage, a shaft rotatably mounted over the second passage and provided with vanes engageable with the plate and arranged to intermittently open and close said passage and push material from the plate therethrough.

4. In a dust collecting system, the combination of a chamber having a passage leading into the top portion thereof at one side thereof, a discharge passage leading from the bottom and opposite side thereof, a baffle plate leading from the first passage to discharge into the second passage, a shaft rotatably mounted over the second passage and provided with vanes engageable with the plate and arranged to alternately close the passage and then open the same and push material therethrough.

5. In a dust collecting system, the combination of a housing forming a dust collecting chamber and having a restricted air outlet formed in the upper portion of one end, a second chamber disposed to overlie the other end of the first chamber, a passage connecting said chambers, a dust conveying passage leading to the top portion of the second chamber, a baffle plate leading from the last named passage to the first named passage, and instrumentalities associated with the first passage disposed to control the flow of air therethrough and to push material from the baffle plate therethrough.

6. The structure set forth in claim 5 wherein the dust collecting chamber is provided with a door spaced from the top of the chamber to provide a narrow passage therebetween and having an inwardly curved shield mounted on the upper portion of its inner side and spaced from the top

of the chamber to form a narrow passage therebetween.

7. The structure set forth in claim 5 wherein the dust collecting chamber is provided with a removable door spaced from the top of the chamber to form a narrow passage therebetween, and a hinged door overlying the first door and spaced from the top of the chamber to form a narrow passage therebetween, and fastening means for the hinged door.

8. In a dust collecting system for shoe repairing machines, the combination with the dust collecting tube and blower, of a tube leading from the discharge end of the blower, a horizontally disposed drum having open communication with the tube at one end and having a slot formed longitudinally in the bottom thereof, a hopper encompassing the slot, a chamber disposed below the hopper and communicating therewith, a chamber disposed below the first chamber and communicating therewith, means operative to

control the flow of air from the first to the second chamber, and means formed in the upper portion of the last chamber to permit continuous flow of air therefrom.

9. In a dust collecting system for shoe repairing machines, the combination with the dust collecting tube and blower, of a tube leading from the discharge end of the blower, a dust settling chamber having open communication with the tube and having a discharge passage formed therein, a hopper encompassing said passage, a chamber disposed below the hopper and communicating therewith, a chamber disposed below the second, or last mentioned chamber and communicating therewith, means operative to control the flow of air from the second to the third chamber, and an air discharge passage formed in the third chamber to permit continuous flow of air therefrom.

JOSEPH BUTERA. 20
